UNITED STATES PATENT OFFICE.

HOWARD JOSEPH HARDING, OF PARIS, FRANCE.

CARBURETOR.

Application filed January 6, 1927, Serial No. 159,406, and in Great Britain January 7, 1926.

This invention relates to carburetors for internal combustion engines of the kind which are adapted for supplying two or more different fuels to the engine, either 5 separately or together in the form of a mixture of fuels.

Carburetors for this purpose have been previously proposed having a separate float chamber and fuel feed system for each of 10 the different fuels, and hand operated control valves have been provided in each of the fuel supply systems, so that the driver can at his own discretion change over from one fuel to another, or alter the proportions 15 of the constituents of the mixture of fuels which is to be supplied to the engine, the arrangement or intention being that petrol or like fuel is used for starting the engine, and when the engine has been running for 20 some time and has acquired a sufficiently high temperature the change over is effected so that the engine runs on a different fuel such as paraffin, or on a mixture of such 25 fuel and petrol.

The primary object of the present invention is to provide a simple form of carburetor which will automatically vary the fuel supplied, or change over from one fuel to another, as the degree to which the fuel 30 is compressed in the engine varies.

Referring to the drawings:-

Figure 1 is a vertical section taken on line 1-1 of Figure 3.

Figure 2 is a side elevation with the cover 35 plate removed.

Figure 3 is a horizontal section taken on line 3-3 of Figure 1.

Figure 4 is a view similar to Figure 2 showing the throttle or controlling valve in 40 a different position.

In the construction illustrated there are two nozzles or fuel supply devices 1, 2, and each nozzle or fuel supply device (or a group of such nozzles or supply devices) receives 45 its supply of liquid fuel from its own float feed chamber or other equivalent device, the nozzle or fuel supply device 1 being supplied with petrol or similar light hydrocarbon from float feed chamber 3 and the other nozzle or fuel supply 2 (or others) being supplied with fuel of a heavier nature 50 such as rectified crude oil from the float feed chamber 4.

The nozzles or fuel supply devices 1, 2 55 may take any suitable form. They may, for instance, consist of hollow tubular bodies

having their ends bent so as to extend longitudinally of a mixing chamber 5 which is of Venturi shape and these hollow tubular bodies are of flat cross section and are provided at their ends near the smallest diameter of the Venturi chamber with slits or openings through which the fuel is discharged.

The mixing chamber 5 is formed in a casing 8, the said casing being formed with the two hollow chambers 3 and 4, the axis of the mixing chamber 5 being at right angles to the axes of the float feed chambers 3 and 4.

The body 8 is provided with two parallel 70 recessed openings 9 in each of which is placed a hollow removable plug 10, openings being provided for the liquid fuel at 11 and 12.

Each plug 10 is fitted with an inner sleeve 75 13, these sleeves being detachable.

The nozzles or fuel supply devices 1 and 2 are secured to the hollow plugs 10 as shewn and the slit like openings at their ends are arranged flush with the surface 14 80 of a recess in the body which forms the chamber for a valve or controlling slide 6.

The nozzles or fuel supply devices 1, 2 are arranged side by side and they are controlled by a transversely sliding throttle 85 valve 6 which is adapted to uncover the petrol supplying nozzle 1 first and subsequently adapted to uncover the other nozzle 2 (or other nozzles) supplying fuel of a heavier nature.

If required, this valve or slide 6 may be constructed with a nose 7 so that, as the nozzle or device 2 supplying the heavier fuel is uncovered, the petrol supplying nozzle or device 1 is covered, the covering of the nozzle or device 1 taking place proportionately with the uncovering of the nozzle or device 2, until finally the engine may be run upon the heavier hydrocarbon alone.

The slide 6 may be operated by a Bowden 100 or other cable 15 and a spring 16 may be provided which engages in a recess 17 in the slide tending to return the slide to its closed position.

The coverplate 18 of the valve or slide 105 chamber is provided with a pipe connection 19 to the engine.

It is, of course, not essential that the throttle controlling the nozzles or their equivalents should take the form of a slide.

It is to be understood that there may be more than two nozzles or groups of nozzles

- or their equivalents and that more than two different kinds or qualities of fuel may be supplied thereby. Further, two or more nozzles or their equivalents may constitute a group receiving fuel from the same source of supply. If desired, one, two or more of the nozzles or of the groups of nozzles may be employed for supplying steam or gas to the mixture in the carburetor.
10. What I claim then is:—
1. In a carburetor, the combination of a mixing chamber having an outlet adapted for connection with the intake of a engine, a plurality of independent feed systems for supplying different fuels, an air inlet, a slide disposed transversely of the mixing chamber and the said air inlet and having an opening allowing the free passage of fuel from the feed systems and air from the air inlet to said mixing chamber, the proportion of air passing to said mixing chamber depending on the position of the slide, a control operating the slide to enable the mixing chamber to be throttled, and a plurality of nozzles for delivering the different fuels from the feed systems to the mixing chamber, said nozzles being disposed with their outlets adjacent a face of the slide, whereby as the passage through the mixing chamber is progressively throttled the outlet of one of the nozzles is progressively restricted in order to decrease the proportion of fuel supplied to an engine from the said nozzle, and, as the opening in the slide is moved to register with the mixing chamber, a projection on the slide extending into the said opening serves to restrict the outlet of a second nozzle progressively, whereby the proportion of fuel supplied to the engine from the said second nozzle is decreased.
  2. In a carburetor, the combination of a mixing chamber having an outlet adapted for connection with the intake of an engine, a plurality of independent feed systems for supplying different fuels, a slide disposed transversely of the mixing chamber and having an opening allowing free passage through the chamber when said opening registers with the chamber, a control operating the slide to enable the mixing chamber to be throttled, a plurality of nozzles projecting into the mixing chamber and serving to

supply the different fuels from the feed systems thereto, cranked extremities on the nozzles extending longitudinally of the chamber, elongated outlet openings to the said nozzles disposed adjacent a face of the slide, whereby as the passage through the mixing chamber is progressively throttled the outlet of one of the nozzles is progressively restricted in order to decrease the proportion of fuel supplied to an engine from the said nozzle, and, as the opening in the slide is moved to register with the mixing chamber, a projection on the slide extending into the said opening serves to restrict the outlet of a second nozzle progressively, whereby the proportion of fuel supplied to the engine from the said second nozzle is decreased.

3. In a carburetor, the combination of a mixing chamber having an outlet adapted for connection with the intake of the engine, an air inlet in the form of a Venturi tube, a plurality of independent feed systems for supplying different fuels, a slide disposed transversely of the mixing chamber and at the narrowest part of the said Venturi tube and having an opening capable of allowing the free passage of air from the air inlet and fuel from the supply systems to the said chamber, a control operating the slide to enable the mixing chamber to be throttled, a plurality of nozzles, having elongated outlet openings, projecting into the mixing chamber and being arranged with their mouths adjacent the said slide and at the narrowest part of the said Venturi tube and serving to supply the different fuels from the feed systems thereto, whereby as the passage through the mixing chamber is progressively throttled the outlet of one of the nozzles is progressively restricted in order to decrease the proportion of fuel supplied to an engine from the said nozzle, and a projection on the slide extending into the opening therein capable of covering the opening in another nozzle, the opening of this nozzle being simultaneously and progressively increased in order to increase the proportion of the other fuel fed to the engine when the opening of the other nozzle is decreased.

In witness whereof I affix my signature.
HOWARD JOSEPH HARDING.
